Inventor
J. B. McIntosh.

United States Patent Office.

J. B. MCINTOSH, OF ERIE, PENNSYLVANIA.

Letters Patent No. 95,250, dated September 28, 1869.

GRATE FOR STOVES AND FURNACES.

The Schedule referred to in these Letters Patent and making part of the same.

To whom it may concern:

Be it known that J. B. MCINTOSH, of the city of Erie, and county of Erie, and State of Pennsylvania, have invented a new and useful Improvement in Grates for Coal-Stoves and Furnaces; and I do hereby declare that the following is a full, clear, and exact description of the construction and operation of the same, reference being had to the annexed drawings, making a part of this specification, in which—

Figure 1 is a plane view, exhibiting the grate as adjusted for use.

Figure 2 is an upright cross-section from A to A, fig. 1.

Figure 3, plane view of cross-bar B, showing the mortise C, in which is fitted the stem D of the star-centre E.

F and G are two rings, placed one above the other, with a series of projecting bars, H and I, on their inner rims.

E is a star-centre, with a stem, D, fitted in mortise C, in a manner that the star-centre E be allowed to vibrate in a circular direction, as occasion may require, for the purpose of throwing ashes, cinder, and clinker from the centre of the grate.

Figure 4 represents the grate, with the upper ring F and its projecting bars I, turned aside, in a manner that the projecting bars I are adjusted over, and to coincide with the projecting bars H, on the bottom ring G, thereby doubling the size of the openings J, and affording a free passage for ashes, cinder, and clinker.

The nature of my invention consists in providing, for coal-stoves and furnaces, grates to support coal in combustion, constructed by the use of two rings, one placed above the other, with bars projecting from their inner rims toward the centre, each alternate bar on the upper and lower rings, that by allowing the bottom ring to be made stationary, and the upper one movable in a circular manner, the openings in the grate may be enlarged, to discharge ashes, cinder, and clinker.

The operation of my improvement is as follows:

The bottom ring, G, with internal-projecting bars H, and cross-bar B, to remain stationary.

The top ring, F, with internal-projecting bars I, so constructed as to allow a circular motion, to admit the projecting bars I to be adjusted over the projecting bars H, thereby doubling the size of the openings J, thus affording a free passage for ashes, cinder, and clinker.

The projecting bars to be made, in number and size, to produce the desired openings in the grate.

I claim—

1. The star-centre E, fixed in mortise C.
2. The construction of a grate, in a manner that the openings J may be enlarged, substantially as described, and for the purpose set forth.

J. B. MCINTOSH.
